UNITED STATES PATENT OFFICE.

ROBERT PERLICK, OF MILWAUKEE, WISCONSIN.

OIL-BURNER.

1,307,064.

Specification of Letters Patent. Patented June 17, 1919.

Application filed September 25, 1918. Serial No. 255,677.

To all whom it may concern:

Be it known that I, ROBERT PERLICK, a citizen of the United States, and resident of Milwaukee, in the county of Milwaukee and 5 State of Wisconsin, have invented certain new and useful Improvements in Oil-Burners; and I do hereby declare that the following is a full, clear, and exact description thereof.

10 My invention is directed to new and useful improvements in oil burners of that type wherein oil is supplied to a burner member including a fuel trough having disposed therein a relatively stationary incombustible

15 wick body of asbestos or the like, and having a depending tube slidable in a supply pipe, the regulation of the flame being procured by raising and lowering the burner bodily to thus vary its relation to the fuel

20 supply level, and my invention relates more particularly to means for procuring movement of the burner member.

It is in general my object to simplify and otherwise improve the structure and to 25 increase the efficiency of devices of this character.

It is more particularly my object to provide a burner operating mechanism which may be constructed mainly of stamped sheet 30 metal and retained in place by its interlocking engagement with the main supply pipe and burner branch of a stove.

A further object resides in the provision of means for adjusting the cap of a packing 35 gland for the burner tube and supply pipe, whereby the cap is normally held against threading movement, and may be readily tightened.

With the above and other objects and advantages in view, which will be apparent as the description proceeds, my invention resides in the novel features of construction, combination and arrangement of parts as hereinafter more particularly described and 45 defined by the appended claims.

In the accompanying drawings:

Figure 1 is a vertical sectional view through an oil burner stove having my improved operating mechanism associated 50 with the burners.

Fig. 2 is a front elevational view of the stove.

Fig. 3 is a rear view of one of my improved burner operating mechanisms, the 55 burner operated thereby being shown in section.

Fig. 4 is a side view of the mechanism, with portions thereof in section.

Fig. 5 is a plan view of the supporting bracket and associated portions of the 60 mechanism.

Fig. 6 is a front elevation of the control handle and indicator dial.

Referring now more particularly to the accompanying drawings, there is shown an 65 oil burning stove including a main burner chamber A having a grid a and having disposed under the grid a series of burners C projecting into hoods D of conventional nature interposed between the burners and grid. 70 A main supply pipe E extends from the fluid level chamber f of a reservoir F disposed at one end of the stove. The constant level chamber is provided in the usual manner with a valved neck portion conventionally 75 designated at g in Fig. 3, whereby a constant level line L may be maintained in such relation to the burners C that the bottom portion of the burners may be moved to lie either above or below this level line, the 80 main supply pipe E being extended longitudinally in the main burner chamber A below the level line and being provided with upstanding supply pipe branches e located in a vertical plane at the forward sides of the 85 burners C, said burners being in the form of annular narrow troughs having their side walls slightly divergent upward for wedging insertion therebetween of an annular wick band c' formed of asbestos or similar 90 non-combustible porous material. Each of the burners is supplied with oil and is supported solely by a depending stem c which is telescopically slidable in a corresponding supply pipe branch e, the degree of sliding 95 movement of the stem permitting the lower portion of the burner to move past the fluid level line L. A packing gland for the stem is provided including a cap c² threaded on the upper end portion of the supply pipe 100 branch and confining packing material between the top of the cap and the end of the pipe branch; said cap being provided with wrench faces, whereby the gland may be tightened as desired incidental to yielding 105 of the packing material in continued operation of the burner.

My improved mechanism for raising and lowering each burner to control the feed of oil through the wick includes a bracket 110 formed of a single plate of metal intermediate bent to form a horizontally extend-

ing arm 10 and a vertically extending arm 11, the inner end portion of the arm 10 being apertured to snugly receive the supply pipe branch *e*. The vertical arm 11 has 5 its lower portion bent laterally forward and then downwardly to provide a shoulder 12 resting on the main supply pipe *E*, and a substantially vertical portion 13 disposed forwardly of and projecting below the pipe. 10 Struck outwardly from the intermediate portion of the bracket arm 11 and bent downwardly below the shoulder is a tongue 14, the main supply pipe *E* being confined between the tongue 14 and arm end portion 13. Upward displacement of the bracket is prevented by a cotter pin 15 passed through the arm portion 13 and the tongue 14 below the pipe, and thus the bracket is firmly secured to the supply pipe 15 structure in a manner permitting a maximum economy in forming the bracket, and a minimum expenditure of labor in assembling the bracket on the supply pipe and branch, the major securing of the bracket 20 being procured simply by the interlocking relations assumed in inserting the supply pipe branch in the apertures of the arms 10 and 11 of the bracket. The forward end of the horizontal bracket arm is downwardly directed at 16 to form an attaching flange to which is secured the lower portion 25 of a vertical dial plate 17.

This downwardly turned bracket arm portion, in conjunction with the lower portion 30 of the dial plate is also utilized to form the journal for the forward end of an operating shaft 18 which extends under the bracket arm at one side of the supply pipe branch *e* and has a second journal in the 35 upper portion of the vertical arm 11 of the bracket. Immediately rearwardly of the arm 11 this shaft is squared for the reception of the headed end of a crank arm 19, the extremity of the shaft being swaged 40 at 20 in Fig. 3 to secure the crank arm on the shaft. Pivoted to the extremity of the crank arm is a link 21 which is also pivoted to the up-turned free end of a lug 22 projecting inwardly from the lower portion 45 of the burner at its juncture with the supporting and supply tube *c*. Thus, upon rotating the shaft 18, the burner *C* may be 50 raised or lowered so that its bottom portion is disposed either above or below the fluid line *L*. To procure this rotation of the shaft, and at the same time procure indication of the position of the burner relative to the fluid level line, the end portion 55 of the shaft outwardly of the dial plate 17 is directed obliquely, and a bar 23 is riveted at an intermediate portion to this oblique end of the shaft, the major portion of the bar extending downwardly to form a handle. The remaining portion of the 60 bar being inclined toward the dial by reason 65

of the attaching portion of the shaft, forms an indicator cooperating with certain symbols on the dial, the handle being spaced forwardly by reason of this oblique inclination to permit a most ready and convenient manipulation thereof. 70

To hold the shaft 18 against longitudinal movement, and also to provide a support for a leaf spring 24 engageable with the head of the link 19, a vertical plate 25 is 75 secured to the side of the bracket adjacent the shaft by the attachment of its laterally turned upper end 26 to the horizontal arm of the bracket, said plate extending rearwardly of the bracket and being provided 80 in its rearward portion with a vertically elongated slot receiving the head of the link 19, the engagement of said head in the slot obviously preventing longitudinal movement of the shaft 18 to which it is attached. 85 The leaf spring 24 is secured at its lower end to the lower rear portion of the plate and bears against that portion of the head which projects through the slot, the head having its periphery rounded concentric 90 with the shaft, whereby a frictional detent is afforded by the spring in the various rotative positions of the shaft, and to hold the burner more positively in normal burning position, and at the same time aid the 95 operator in attaining this normal burning position, the head of the link is provided with a notch 27 in which the transversely bowed free extremity of the spring engages when the link 19 is disposed in a substantially horizontal position, procuring a 100 position of the burner intermediate of its limits of vertical movements, the lower edge of the wick being disposed slightly below the fluid level line *L* in this position. 105

It is noted that the link may swing through an arc of substantially 180°, engaging in either limit of movement against the rearward portion of the wall plate 25, and in its upward limit of movement, it is noted that 110 the upper end of the link swings for abutment with the plate, slightly past a dead center line connecting the axis of the shaft 18 with the pivotal axis of the burner lug 22, whereby the burner is thus locked in raised 115 position.

The indicator dial 17 is provided with symbols 28 and 29 at opposite sides of the shaft 18 indicating respectively the upper and lower limits of movement imparted to 120 the burner by the handle and indicator bar 23, the burner being raised to its limit of upward movement, consequently cutting off supply of oil thereto when the indicator points to the symbol 29, and being depressed 125 to its lower limit of movement when the indicator points to the symbol 28 to supply an excess of oil to the burner to facilitate lighting the burner. Intermediate of the symbols 28 and 29 there are provided a series of 130

symbols 30 adapted to indicate various burning positions, the normal burning position of the burner as indicated by the central symbol 30, corresponding to the position of 5 the crank arm 19 when the notch 27 of its head is engaged by the detent spring 24.

Continued raising and lowering movements of the burners loosens the packing glands of the supporting tube *c*, and it is 10 necessary from time to time to tighten the gland caps *c*², to take up this looseness. I provide a tightening means for the cap in a most compact and readily operated manner, which means is associated permanently with 15 the burner structure as is necessary in a commercially attractive article. Thus, a wrench is provided including an annular closed head 31 apertured to receive the cap, this wrench head being provided with upwardly and inwardly extending fingers 32' adapted to seat on the cap. A downwardly offset handle 32 extends from the wrench head and is provided with a slot 33 which normally receives a finger 34 struck upwardly from the horizontal arm 10 of the bracket, whereby a lock for the cap is normally afforded preventing any tendency to unscrewing movement which would be set up in operation of the burner. To tighten the cap *c*², it is merely necessary 20 to lift the wrench handle 32 from engagement of the finger 31 in its slot 33, and then to rotate the wrench and cap, the wrench being subsequently engaged with other wrench faces of the cap and restored to its 25 locking co-action with the finger 34.

An exceedingly simple device has thus been provided for tightening the cap which may be readily manipulated by persons not necessarily familiar with mechanical operations, it being noted that a maximum compactness of structure is permitted in contradistinction to heretofore contemplated arrangements. Attention is further directed to the fact that loss of the wrench is positively prevented by reason of the closed 45 shape of its head, so that the head is interlocked at all times either on the cap or with respect to the tube *c*.

It will be particularly noted that by the 50 disposition of the supply tube *c* and the connecting link 21 at the forward side portion of the burner C, the center of gravity of the burner is disposed a considerable distance laterally thereof, and thus a frictional binding action is set up which normally holds the burner against downward movement under influence of gravity, this holding being relied upon to maintain the burner in its 55 various burning positions other than the intermediate normal burning position in which the spring 24 engages in the notch 27 of the head of the crank arm 19, said spring also, of course exerting some frictional action against the periphery of the head when disengaged from the notch.

I claim:

1. A burner of the class described including a main supply pipe, a branch pipe upstanding therefrom, a burner trough, a depending tube carrying said trough, and 70 slideable in the branch pipe, an angular bracket plate apertured in its intermediate portion to receive the supply pipe branch and having one end portion branched to embrace the supply pipe whereby to secure the 75 bracket on the supply pipe, and means carried by said bracket for raising and lowering the burner trough.

2. A burner of the class described including a main supply pipe, a branch pipe extending therefrom, a burner trough, a depending tube carrying said trough and slideable in the branch pipe, an angular bracket plate including a vertical arm secured at its lower end to the main supply pipe, and a 80 horizontal arm apertured adjacent the vertical arm to receive the supply branch, the outer portion of the horizontal arm being bent downwardly to form an attaching flange, a dial plate secured to said flange, 85 an operating shaft journaled in the flange and the vertical arm of the bracket, an indicator on the outer end of the shaft co-operating with the dial plate, and an operative connection between the inner end of the 90 shaft and the burner trough for raising and lowering said burner trough upon rotation of the shaft.

3. A burner of the class described including a main supply pipe, a branch pipe upstanding therefrom, a burner trough, a depending tube carrying said trough and slideable in the branch pipe, an angular bracket plate including a horizontal arm apertured at its inner portion to receive the branch pipe, and a vertical arm having its lower portion laterally offset to form a consequent shoulder seating on the main supply pipe, an ear out-struck from the vertical arm and bent downwardly, a securing member passed 105 through said ear and the lower offset portion of the vertical arm below the main supply pipe, and means carried by the bracket 110 for raising and lowering the burner.

4. A burner of the class described including a main supply pipe, a branch pipe upstanding therefrom, a burner trough, a depending tube carrying said trough and slideable in the branch pipe, an angular bracket plate including a horizontal arm apertured at its inner portion to receive the branch pipe, and a vertical arm, the lower portion of the vertical arm being bent to embrace and seat on the main supply pipe, and means 120 carried by the bracket for raising and lowering the burner trough.

5. A burner of the class described including a main supply pipe, a branch pipe upstanding therefrom, a burner trough, a depending tube carrying said trough and slid-

able in the branch pipe, an angular bracket plate including a horizontal arm apertured at its inner portion to receive the branch pipe, and a vertical arm having its lower portion laterally offset to form a consequent shoulder seating on the main supply pipe, said shoulder being apertured for the reception of the branch pipe, and means carried by the bracket for raising and lowering said burner trough.

6. A burner of the class described including an upstanding supply pipe, a burner trough, a depending tube on said burner trough slideable in the supply pipe, a bracket secured to the supply pipe, a cap surrounding the supply tube and threaded on the upper end of the supply pipe and provided with wrench faces, a permanently associated wrench including a head portion engageable on said cap and prevented from detachment by the burner trough tube upon disengaging the cap, means carried by the bracket for holding the wrench against rotation, and means for raising and lowering the burner trough.

7. A burner of the class described including an upstanding supply pipe, a burner trough, a depending tube carrying said burner trough and slideable in the supply pipe, a packing cap surrounding the tube and threaded on the upper end of the supply pipe and provided with wrench faces, an annular wrench head engageable on the cap, a handle extending from said wrench head, means for preventing rotation of said

handle, and means for raising and lowering the burner.

8. A burner of the class described including an upstanding supply pipe, a burner trough, a depending tube on said burner trough slideable in the supply pipe, a bracket secured to the supply pipe and including a horizontally extending portion, a cap surrounding the supply tube and threaded on the upper end of the supply pipe and provided with wrench faces, an annular wrench head engageable on the cap, a handle extending from said wrench head and provided with a longitudinal slot, an upstanding finger on the bracket engageable in said slot to hold the wrench against rotation on the cap, and means for raising and lowering the burner trough.

9. A burner of the class described including a main supply pipe, a branch upstanding therefrom, a bracket secured to the branch pipe, an operating shaft journaled in said bracket, a plate secured to said bracket and provided with a vertically elongated slot, a crank member on the shaft having a circular head enlargement concentric with the shaft and projecting through the slot of the plate, and a spring secured on the plate and bearing against the peripheral portion of said head projecting through the slot.

In testimony that I claim the foregoing I have hereunto set my hand at Milwaukee, in the county of Milwaukee, and State of Wisconsin.

ROBERT PERLICK.
